Inventor

Charles W. Carol,

By Samuel Herrick

Attorney

UNITED STATES PATENT OFFICE.

CHARLES WATTS CAROL, OF GLOBE, ARIZONA.

CHICKEN HOVER.

Application filed June 4, 1923. Serial No. 643,374.

To all whom it may concern:

Be it known that CHARLES WATTS CAROL, citizen of the United States of America, residing at Globe, in the county of Gila and State of Arizona, has invented certain new and useful Improvements in Chicken Hovers, of which the following is a specification.

This invention relates to a chicken hover and it has for its object to provide a simple and inexpensive device of this character constructed in such manner that the chicks may be maintained in a sufficiently warm and protected condition without the use of artificial heat, while at the same time the necessary limited ventilation may be supplied to the compartment in which they are located.

Further objects and advantages of the invention will be set forth in the detailed description which follows.

In the accompanying drawing:

Fig. 1 is a side elevation of a chicken hover constructed in accordance with the invention;

Fig. 2 is a longitudinal sectional view therethrough; and

Fig. 3 is a transverse sectional view therethrough.

Like numerals designate corresponding parts in all of the figures of the drawing.

Referring to the drawing 5 designates an outer box which is preferably of rectangular formation and 6 designates an inner box suitably spaced from the outer box to provide a dead air space 7 therearound. To completely separate this air space 7 from that part of the outer box which lies above the top of the inner box filling strips 8 are employed. A doorway 9 is formed through an end wall of the box and is preferably provided with a door 10 and a run-way 11 leading to said doorway through which the chicks may enter the compartment 12 formed within the inner box. The strips 8 along the sides of the box support slats 13 and these slats, in turn, support a sheet of loose cotton 14, which is preferably quite thick and through which the body gases and breath of the chicks in the compartment 12 slowly

filter and find their way to the outside air through ventilating holes 15 bored in the side of the box above the line of said cotton. This cotton is raw cotton and may be in the form of cotton batting, in sheets, or it may be in loose formation. The outer box is provided with a lid 16 and I contemplate covering the outside of the inner box with one or more sheets of paper, indicated at 17, to further insulate the inner box against cold and to prevent sudden changes of temperature.

The door 10 is normally left open for the entry of fresh air. However, this door is employed, when desired, to prevent the escape of the chicks from the hover in moving the hover from place to place.

It is to be understood that the invention is not limited to the precise construction set forth but that it includes within its purview whatever changes fairly come within either the terms or the spirit of the appended claim.

Having described my invention, what I claim is:

A hover of the character described comprising an inner box and an outer box, a filling strip therebetween adjacent the upper end of the inner box and below the top of the outer box whereby a dead air space is formed between the inner and outer boxes below said strip, a doorway leading from the outside to the interior of the inner box, a covering of loose cotton constituting the top of the inner box and permitting a gradual seepage of air therethrough throughout its area and a cover for the outer box, there being a plurality of spaced openings formed in the sidewalls of the outer box above the level of said inner box and in the transverse plane thereof, whereby ventilation is equalized at all points in the length of the hover.

In testimony whereof I affix my signature in the presence of two witnesses.

CHARLES WATTS CAROL.

Witnesses:

EDWARD H. GILLILAND,
GEO. W. EDWARDS.
